HANDKERCHIEF HOLDER

Billy Erik Olsson, 4107 N. Major Ave., Chicago, Ill.

Filed May 7, 1958, Ser. No. 733,670

5 Claims. (Cl. 24—3)

This invention relates to sartorial equipment and more particularly to means for retaining a folded handkerchief in observable position in the coat or jacket pocket of a wearer.

Present day fashion approves of the display in a coat or jacket pocket of the upper edge of a folded handkerchief. The exposure of just the right amount of such a handkerchief, however, involves not only accurate folding but the employment of a handkerchief possessing sufficient stiffness to resist crumpling and sliding down out of sight in the pocket.

The main purpose of my present invention is to provide a holder which will hold a folded handkerchief in the requisite position for display.

Another object is to provide a holder one portion of which may be permanently attached to a wall of the handkerchief pocket and the other portion of which after being attached to a folded handkerchief may be detachably mounted upon that portion attached to the pocket.

Another purpose of my invention is to provide a holder which will extend substantially the full width of the folded handkerchief but which by reason of being made in separate parts will not distort or give the appearance of stiffness to the garment to which it is applied.

Another object is to provide a handkerchief holder which can be applied to a handkerchief either within a pocket or outside the pocket so as to enable the proper folding of the handkerchief and the application of the holder thereto before it is placed in the pocket.

Other objects and advantages of the invention will be apparent when the same becomes better understood from the following description when considered in connection with the accompanying drawing.

Referring to the drawing:

Figure 1 is a perspective view showing my novel holder in operative position;

Fig. 2 is a fragmentary sectional view on the line 2—2 of Fig. 1;

Fig. 3 is a front view of a stationary member of my novel holder;

Fig. 4 is a rear view of the detachable clip portion of my holder; and

Fig. 5 is a rear view of a stationary and a detachable member in assembled relation.

Referring to the drawing more in detail, the holder illustrated embodying my invention which at present is the preferred form comprises a pair of holding devices indicated generally by reference characters 6 and 7, respectively. Each holding device comprises a supporting member 8 composed of sheet metal, plastic, or other preferred material shaped to provide a flat plate-like body provided at one edge with one or more notches 9 and with locking openings 11, the locking function of which will be later explained. Each plate-like member 8 is also provided with apertures 12 through which fastening threads may be threaded to attach the holding members to the inner wall of the user's pocket, which

2

is outlined in dotted lines and indicated by reference character 14.

The companion or cooperating member of each holding device consists of a similar plate-like member 15 provided with a clip or clamping element 16 preferably formed integrally with the body of the member 15 and tempered so as to form a resilient clip or clamp. The body of the member 15 is stamped to form the rearwardly and downwardly projecting hooks 17 spaced apart in conformity to the spacing of the notches 9 and adapted to be engaged therewith. These hooks are provided with indentations or protrusions 18 designed to interengage with the locking openings 11 of the member 8 to lock the two members 8 and 15 together, as illustrated in Fig. 5.

My novel holder consisting of the pair of holding devices is intended for use in the following manner. The supporting members 8 are attached to the face of the rear wall of a garment pocket 14 a short distance below the upper edge of the pocket, as indicated in Fig. 1. This attachment of the holding members is effected by sewing with the use of threads 13 or by a detachable mounting such as a pin or a snap fastener. The holding devices are attached in spaced apart relation, as shown, in order not to interfere with the flexibility of the material of the garment sufficiently to distort the same or cause a clumsy and stiff appearance.

After the garment has been equipped with the supporting members in the manner above indicated, the handkerchief, which is indicated in Fig. 1 by reference character 19, is folded to a width such that it may be readily inserted in the pocket, whereupon the members 15 are slipped over the edges of the folded handkerchief so that the clips 16 engage and embrace the margins of the handkerchief. The handkerchief with the clips attached is now inserted in the pocket and the clamping members 15 are attached to the supporting member 8 by engaging the hooks 17 in the notches 9 of the supporting members, as shown in Figs. 1 and 5. The holder, now being clamped to and firmly holding the handkerchief against movement either up or down, retains the handkerchief in the desired position with just the right amount of margin exposed above the pocket. Interengagement of the cooperating locking elements 11 and 18 prevents the holding clips from becoming detached from the supporting members 8. Displacement of the handkerchief from the desired position is, therefore, prevented by the employment of my novel holder by which the handkerchief is retained in smooth condition and in a position to prevent a neat and attractive appearance.

My invention also contemplates attachment of the clip members to the supporting members in the pocket before the handkerchief is attached. In such event the margins of the handkerchief may be inserted beneath the clips already mounted in the pocket.

In practice, the user may purchase an equal number of supporting members 8 and clip members 15 so that each of several garments may be equipped with a complete holding set or, for purposes of economy, a lesser number of holding clips may be purchased and may be transferred from one garment to another.

Irrespective of the manner of use, the flat supporting members remaining in the pocket after removal of the clip members offer no obstruction to either hand or machine pressing of the garment. Interference with the pressing operation could also be eliminated by removably attaching the clip members directly to the inner wall of the pocket by a pin or similar removable clip supporting means.

While I have referred herein specifically to a "handkerchief" the term is used in a generic sense to include not only a useful article but also an article capable of

use only as an adornment such as a small piece of fabric so folded and held in the holder of my invention as to simulate a real handkerchief.

It should be apparent from the foregoing that a handkerchief holder embodying my invention may be economically manufactured and readily installed in a garment to securely hold a handkerchief or a simulated handkerchief in the desired position so that the requisite area will be displayed above the top of the pocket.

The material employed and the size and structural details of the holder may obviously be varied within considerable limits without departing from the essence of my invention as defined in the following claims.

I claim:

1. A handkerchief holder for retaining a folded handkerchief in observable position in a pocket of the coat of a wearer, comprising a pair of horizontally disposed supporting members for attachment in spaced relation to the inner wall of said pocket below the opening thereof so as to be hidden from view, each of said members being provided with vertically opening, spaced notches and retaining means, and a pair of companion horizontally disposed holding members each provided with downwardly projecting spaced hooks received in and having detachable engagement with said notches and with retaining means cooperable with the retaining means of said supporting members, said holding members being provided with open ended inwardly projecting clips for the reception of the vertical marginal edges of said folded handkerchief whereby said handkerchief is supported and retained in predetermined position in said pocket, said supporting and holding members being each disposed within and below the opening of said pocket.

2. A handkerchief holder for retaining a folded handkerchief in observable position in a pocket of the coat of a wearer, comprising a pair of elongated and substantially horizontally disposed flat supporting members constructed for attachment to the inner wall at the rear of said pocket below its opening so as to be hidden from view, each of said members being provided with a pair of upwardly opening notches and retaining means, and a pair of holding members each including a substantially horizontally disposed flat body and an inwardly opening spring clip at its outer end, said holding members being provided with downwardly projecting hooks positioned to be received in the notches of one of said supporting members and having companion retaining means for engagement with the retaining means of said supporting members for detachably locking said members together below the opening of the pocket so as to be hidden from view.

3. A handkerchief holder for retaining a folded handkerchief in observable position in a pocket of the coat of a wearer, consisting of a substantially horizontally arranged and elongated flat supporting member affixed to an inner wall at the rear of said pocket and provided with spaced notches along its upper edge and retaining

means, and a substantially horizontally arranged and elongated flat holding member provided with spaced hooks and retaining means for cooperative engagement with the notches and retaining means of said supporting member and with an inturned spring clip at its outer end for engaging and holding the vertical margin of a folded handkerchief, said members being disposed within and below the opening of said pocket so as to be hidden from view.

4. A handkerchief holder for retaining a folded handkerchief in observable position in a pocket of the coat of a wearer, comprising a pair of substantially horizontally arranged and spaced supporting members constructed and proportioned for attachment in spaced relation to the inner face of said pocket below the opening thereof so as to be hidden from view, a pair of spaced and substantially horizontally arranged holding members each having an inwardly projecting clip part at one end to receive and retain therein the spaced vertical margins of said folded handkerchief, and cooperating detachable locking means carried by said supporting and holding members including spaced locking openings in each supporting member and spaced hooks on each of said holding members having indentations with said hooks engaging said supporting members and said indentations received in said openings, whereby said holding members are detachably attached and supported by said supporting members wholly within the pocket and thus hidden from view.

5. A handkerchief holder for retaining a folded handkerchief in observable position in a pocket of the coat of a wearer, comprising a pair of substantially horizontally arranged flat supporting members having openings adjacent each end of said members for attachment of said members in spaced relation to the inner face forming the rear of said pocket, said members having other openings intermediate the ends thereof, and handkerchief engaging and holding means for detachable engagement with said supporting members, said holding means including substantially horizontally disposed spring clips for engaging and retaining the vertical margins of the folded handkerchief and hook members having indentations for interlocking engagement with the spaced intermediate openings in said supporting members, said supporting members and holding means being disposed wholly within the pocket to be hidden from view.
